UNITED STATES PATENT OFFICE.

PAUL POLIZZI, OF SAN FRANCISCO, CALIFORNIA.

INTERNAL-COMBUSTION ENGINE.

Application filed April 11, 1927. Serial No. 182,773.

This invention relates particularly to an internal combustion engine.

An object of the invention is to provide an internal combustion engine having plural cylinders, each cylinder being provided with an oscillating piston pivotally mounted therein, and independent combustion chambers on opposite sides of the said piston to effect oscillating movement thereof.

10 A further object of the invention is to provide an internal combustion engine having a plurality of cylinders, each cylinder shaped as an inverted pyramid and having a rectangular piston pivoted therein at the apex of the cylinder, and each piston pivotally connected to a crank shaft.

20 A still further object of the invention is to provide in an internal combustion engine a cylinder shaped as an inverted, rectangular pyramid and in which a rectangular piston is pivotally mounted at the apex of the cylinder, said piston having an extended arm thereon extending into the cylinder crank case to be connected by suitable mechanism to the engine crank shaft.

30 Other objects of the invention are to provide an internal combustion engine that will be superior in point of simplicity, inexpensiveness of construction, positiveness of operation, and facility and convenience in use and general efficiency.

35 In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention 40 in whatsoever form it may be embodied.

In the accompanying one sheet of drawings

Fig. 1 represents a vertical section taken through a single cylinder of an internal combustion engine constructed in accordance 45 with my invention.

Fig. 2 is a plan view of a plurality of cylinders of the type shown in Fig. 1.

Fig. 3 is a section taken through a plurality of cylinders on the line 3—3 of Fig. 1.

Fig. 4 is a perspective view of one of the cylinder pistons broken away to show the interior construction thereof, and diagrammatically illustrated in connection with a 55 lubricating pump.

In detail the construction illustrated in

the drawings comprises the crank case 1 of an internal combustion engine, having a crank shaft 2 with a plurality of throws or eccentrics 3 journaled therein. The number of throws or eccentrics on the crank shaft 2 will correspond with the number of pistons in the engine.

A cylinder block 4, that is suitably water jacketed at 5 around the sides and top thereof, is mounted upon the crank case 1. The cylinder block is provided with a plurality of cylinders 6, 7, 8 and 9 therein. Each cylinder is rectangular in cross section, and shaped as an inverted pyramid. The apex 70 of the cylinder is arranged adjacent the crank case 1, while the base of the said cylinder is extended above the crank case.

A rectangularly shaped piston 10 is arranged in each cylinder. Each piston, at the bottom thereof, is provided with a circular bearing 11 thereon to be confined in a journal 12 formed at the bottom or apex of each cylinder. The pistons 10 are arranged in each of the cylinders whereby the axis of the bearing 11 on each piston will lie substantially parallel to the axis of the crank shaft 2. Shafts 13 extend from opposite ends of each of the piston bearings 11 and said shafts 13 are journaled in bearings 14 formed in the cylinder block. The bearings 11 and the shafts 13 on each of the pistons 10 are arranged in axial alignment in the cylinder block whereby all of the pistons 10 will oscillate about the same axis.

90 Each of the bearings 11 and shafts 13 are drilled lengthwise to permit a lubricant to be forced through the pivoted and connected ends of the pistons from a conduit 15 that is connected to a lubricant pressure pump 16 operated in synchronism with the engine. The piston bearing 11 is provided with openings therein to permit lubricant to be forced into the piston journal 12.

100 The two side edges and upper end each of the piston 10 are provided with a continuous slot or recess 17 therein, in which side and top pressure strips 18 are movably mounted. Expansion springs 19 are mounted in the base of the groove 17 around the piston to move the expansion strips 18 outwardly into engagement with the sides and top wall of the cylinder to prevent combustion pressure losses. Each of the strips 18 are movable independent of the other whereby they may adjust themselves to the inner contour of the cylinder, and to form a snug

joint between the entire perimeter of the piston and the walls of the cylinder. The piston 10 is drilled longitudinally and laterally with oil holes 20, all of which communicate with the hollow center 21 of the piston bearing 11 to receive a source of lubricant supply therefrom. The movable bars 18 on the edges of the piston are likewise drilled at 22 to permit the passage of lubricant therethrough and into contact with the walls of the cylinder.

An arm 23 is provided on the bearing end of each piston 10 that extends into the crank case 1. The extended arm 23 on each piston 15 is connected by a connecting rod 24 to one of the throws on the engine crank shaft. The various throws on the crank shaft 2 are offset thereon in proper relation, whereby when the connecting rods 24 are connected 20 to the crank shaft 2 and to the respective pistons 10, the said pistons 10 will be located in proper timing relation within each of the cylinders.

Combustion chambers 25 and 26 are recessed on opposite sides of each cylinder whereby the combustion chamber 25 will lie on one side of the piston 10 and the combustion chamber 26 on the opposite side of the piston. Each of the combustion chambers 30 are provided with the inlet and outlet ports 57 and 58 respectively therein. The inlet ports 57 along one side of each of the connected cylinders communicate with an intake manifold 29 which has a carbureting device 30 thereon while the inlet ports 57 along the opposite sides of the same cylinders communicate with an intake manifold 31 connected to a carbureting device 32. The exhaust or discharge ports 58 on both of the 35 opposite sides of the engine cylinders are connected to a common exhaust manifold 33. Valves 27 and 28 are slidably mounted in each of the respective inlet and outlet ports. Each valve is slidably mounted in a bearing 40 formed in the respective inlet or outlet ports and each valve is held in the closed position by an expansion spring 35 arranged exteriorly around the stem of each valve.

A cam shaft 36 is rotatably journaled 50 over the upper end of all of the cylinders in parallel alignment with the axis of the engine crank shaft. A timing gear 37 is provided on one end of the cam shaft, and is connected by a drive chain 38 or other equivalent driving mechanism to a timing gear 39 provided on a projecting end of the engine crank shaft 2. The diameters of the timing gears on the cam shaft and crank shaft are proportioned so that the proper timing between the cam shaft and crank shaft will be maintained to open and close the various inlet and outlet valves 27 and 28 during each of the various cycles of operation of the engine.

A plurality of standards 40 are provided 65 along the upper end of the various engine cylinders adjacent the cam shaft 36. A rocker arm 41 is pivoted at 42 intermediate its ends whereby an end 43 of said rocker arm will rest on the cam shaft 36 and the 70 opposite end 44 of the rocker arm will rest against one of the valve tappets on the left side of the cylinders. Thus as the cams on the cam shaft 36 rotate to engage the end 43 of the rocker arm, the said rocker arm is 75 oscillated and the end 44 thereof moved into engagement with a valve tappet to open the valve. After the pressure of the rocker arm is released from the valve, the expansion spring 35 on said valve, causes the valve to 80 be brought to the normally closed position. A rocker arm 46 is pivoted to the standard 40 at an end 47 thereof, said last mentioned rocker arm being arranged beneath the cam shaft 36 and having the free end 48 thereof 85 in engagement with the projecting stems of the valves on the right side of the engine. The rocker arm 46 is moved downwardly by the cams on the cam shaft 36 to open the 90 various valves and said valves are returned to the closed position by the expansion springs therearound. It is obvious that the cams on the cam shaft will be arranged thereon in proper position to actuate the valve rocker arms to effect opening movement of the various valves in proper sequence in the cycle of operation of the engine. In accordance with standard practice, each of the combustion chambers 25 and 26 are provided with spark plugs 49 or some 95 other type of sparking device, for igniting the combustible mixture in the combustion chamber.

My engine operates on the four cycle principle, wherein on the first cycle a charge of 105 combustible material is drawn into the engine cylinder; on the second cycle the charge is compressed by the action of the piston moving in the cylinder; on the third cycle the compressed combustible mixture is 110 ignited and on the fourth cycle the burned products of combustion are exhausted from the cylinder.

In Fig. 1 of the drawings a combustible mixture is confined between the piston and 115 cylinder, on the left side of the engine, while a combustible charge is about to be admitted into the combustion chamber on the right side of the cylinder. The movement of the piston into the dotted position shown in 120 Fig. 1 causes the combustible mixture on the left side of the piston to be compressed and a charge of combustible material to be drawn into the chamber on the right side. On the succeeding cycle the combustible mixture in 125 the left side combustion chamber is ignited while combustible charge on the right side of the piston would be compressed. On the

- next cycle the combustible charge on the right side of the piston is exploded and the products of combustion on the left side of the piston are exhausted from the cylinder.
- 5 On the last cycle a charge of combustible material is drawn into the cylinder on the left side of the piston while the burned products of combustion on the right side of the piston are exhausted from the cylinder.
- 10 Each of the various four cycles of operation are then repeated. My experiments have determined that an engine constructed in accordance with my invention will develop greater horse power per unit of fuel consumed and per weight of engine.

Having thus described this invention, what I now claim and desire to secure by Letters Patent is—

1. An internal combustion engine having a cylinder with a pair of independent combustion chambers on opposite sides thereof; a piston pivoted at the bottom end of said cylinder to separate said combustion chambers; an arm extended from the lower end 25 of the piston; a link connecting said piston arm to a crank shaft; and means operable in relation to the cylinder piston to charge, compress and combust a combustible mixture in each chamber and discharge said mixture from said chamber to effect oscillating movement of the piston.

2. An internal combustion engine consisting of a cylinder shaped as an inverted pyramid and having a pair of independent 35 combustion chambers on opposite sides of the base thereof; a piston pivoted at the apex of the cylinder to separate the combustion chambers; an arm extended from the lower end of the piston; a link connecting said piston arm to a crank shaft; and means operable in relation to the cylinder piston to charge, compress, and combust a combustible mixture in each chamber and discharge said mixture from said chamber 40 to effect oscillating movement of the piston.

3. An internal combustion engine having a cylinder with a pair of independent combustion chambers on opposite sides thereof; a piston pivoted at the bottom end of said cylinder to separate said combustion chambers; an arm extended from the lower end of the piston; a link connecting said piston arm to a crank shaft; an inlet and outlet port in each of the combustion chambers on opposite sides of the cylinder; and means to actuate said ports in synchronized relation to the movement of the piston to permit a combustible charge to be entered, compressed and ignited in and discharged from each combustion chamber on opposite sides of the piston to effect oscillating movement of the piston.

4. An internal combustion engine consisting of a cylinder shaped as an inverted pyramid and having a pair of independent

combustion chambers on opposite sides of the base thereof; a piston pivoted at the apex of the cylinder to separate the combustion chambers; an arm on the piston extended below the apex of the cylinder; a connecting rod to connect the piston arm to a crank shaft to convert oscillating movement of the piston into rotary movement of the crank shaft; an inlet and outlet port in each of the combustion chambers on opposite sides of the cylinder; and means to actuate said ports in synchronized relation to the movement of the piston to permit a combustible charge to be entered, compressed and ignited in and discharged from each combustion chamber on opposite sides of the piston to effect oscillating movement of the piston.

5. An internal combustion engine consisting of a cylinder shaped as an inverted pyramid and having a pair of independent combustion chambers on opposite sides of the base thereof; a piston pivoted at the apex of the cylinder to separate the combustion chambers; an arm on the piston extended below the apex of the cylinder; a connecting rod to connect the piston arm to a crank shaft to convert oscillating movement of the piston into rotary movement of the crank shaft; and valve means to allow a combustible charge to enter, and to evacuate the products of combustion from each combustion chamber, said valve means being synchronized to move with the piston to permit a combustible charge to be compressed and exploded on opposite sides of the piston to effect oscillation thereof.

6. An internal combustion engine consisting of a cylinder shaped as an inverted pyramid and having a pair of independent combustion chambers on opposite sides of the base thereof; a piston pivoted at the apex of the cylinder to separate the combustion chambers; an arm on the piston extending below the piston pivot; and means operatively connecting said arm to a crank shaft to convert oscillating movement of the piston into rotary movement of the crank shaft.

7. An internal combustion engine consisting of a cylinder shaped as an inverted pyramid and having a pair of independent combustion chambers on opposite sides of the base thereof; a crank case adjacent said cylinder; a piston pivoted at the apex of the cylinder to separate the combustion chambers; an arm on the piston extending into the crank case; and means operatively connecting said arm to a crank shaft to convert oscillating movement of the piston to rotary movement of the crank shaft.

In testimony whereof, I have hereunto set my hand at San Francisco, California, this 30th day of March, 1927.

PAUL POLIZZI.
